UNITED STATES PATENT OFFICE.

CONRAD DE STAEBLER, OF ST. LOUIS, MISSOURI, ASSIGNOR OF ONE-THIRD
TO BENJAMIN R. BONNER, OF SAME PLACE.

STREET-CAR ATTACHMENT.

SPECIFICATION forming part of Letters Patent No. 269,161, dated December 12, 1882.

Application filed May 31, 1882. (No model.)

To all whom it may concern:

Be it known that I, CONRAD DE STAEBLER, of the city of St. Louis, in the State of Missouri, have invented a certain new and useful Improvement in Street-Car Attachments, of which the following is a full, clear, and exact description, reference being had to the accompanying drawings, forming part of this specification, and in which—

10 Figure 1 is a bottom view of a car with my improvement attached. Fig. 2 is a front view, and Fig. 3 is a side elevation.

15 My invention relates to a device which is automatically operated to apply the brakes to the wheels in the event of an object of any considerable size being on the track, avoiding all danger of people being run over by street-cars. While my device applies the brakes instantaneously, it is also provided with a means 20 for moving the object should the car not be stopped before the wheels reach it.

A represents the side strips, B the end strips, C the axles, and D the wheels, of a common street-car.

25 E is the brake-lever, connected to the brake-beams F F by rods G G, as usual, and having at its opposite ends the usual pull-chains, H H.

I is a bar connected by one end to the lever E, bent at I' to throw its free end up above the axle, as shown. The bar I has teeth J, which at the proper time engages a ratchet-wheel, K, rigidly secured to the axle C, so as to turn with it. Thus the brakes are instantaneously applied by dropping the bar into the ratchet-wheel. The free end of the bar rests upon and is held up out of engagement with the ratchet-wheel by a cross-bar, L, connecting two 30 L-shaped guards, M M, pivoted respectively at N N to the side strips, A, of the car. As the

40 guards are pivoted near their forward ends it will be seen that their rear ends, when permitted, will drop into the position shown by dotted lines, Fig. 3, which will allow the bar to engage the ratchet-wheel, and should the object be reached before the car is quite stopped it will be moved by the lower ends of the 45 guards. The end of the bar I is straddled by the lower ends of a lifting-bar, O, which are secured to the cross-piece L, and is thus kept

from lateral movement. The purpose of the 50 bar O is to lift the guards into their elevated position. It would pass up through the bottom of the car, and it would preferably have teeth to engage with a plate, P, to prevent the parts being thrown up by the motion of the 55 car.

I will now describe the means for holding the guards in their elevated position and for tripping them when a person or object on the track is approached: They have upturned 60 ends Q, which, when their free ends are in their natural or upper position, engage with notches R' in the upper ends of vertical bars or hangers R, pivoted to the car-body. By these hangers R the guards are held in their natural or 65 normal position; and it will be seen that when their lower ends strike an object their upper ends will be disengaged from the guards, allowing the brake-bar I to drop. The lower ends of the bars R are connected, so that should 70 one strike an object the other will be operated also. Likewise, should the object be in the middle of the track, both bars will be operated by the cross-bar striking the object. The purpose or main design of my invention is to prevent 75 people being run over by street-cars; so the lower ends of the bars R should be about six or eight inches from the ground, or low enough to strike the body of a small child. The bars R may be connected by a plain strip; but I prefer to use a connecting-piece that will admit of a slight vertical movement on a directly-upward pressure being brought upon it—as, for instance, when the car is rocked unusually hard by a rough crossing, &c.—to avoid damage to 85 and an unnecessary operation of the parts. To this end I turn outward and form holes in the lower ends of the vertical bars R, and insert in these holes the upturned ends S' of a connecting piece or bar, S. The ends S' are 90 hammered to form heads, preventing them from dropping out.

To the bottom of the car is secured a hanger, T, whose out-turned lower end receives the stem U of a yoke, V, which has journalized in 95 it a small wheel, W. On the yoke are two arms, X, which extend back beneath the bar S. Thus it will be seen that on the excessive

rocking of the car the wheel W will strike the ground and raise the connecting-bar S.

I have shown my invention secured to one end of a car; but as a matter of course its duplicate would be attached to the other end also.

I have shown and described my invention as applied to a street-car; but it may be applied to other vehicles.

I claim—

10. 1. In a safety attachment for street-cars, the combination of brake-beams F, rods G, lever E, bar I, wheel K, rigidly secured to the car-axle, and guard or guards M, all arranged and operated substantially as and for the purpose set forth.

15. 2. The pull-rod O, secured to the guard-bar L and straddling the end of the brake-bar I, substantially as and for the purpose set forth.

3. The guards M, pivoted to the car-body

and having upturned ends Q, in combination 20 with notched vertical bars R, arranged to hold the guards in their elevated position and to drop them at the proper time, as set forth.

4. The cross-piece S, connected to the bars R, so as to have a vertical movement, in combination 25 with the hanger T, yoke U V, arms X, and wheel W, substantially as and for the purpose set forth.

5. The combination of brake-beams F, rods G, lever E, bar I, wheel K, guards M, pull-rod 30 O, vertical bars R, connecting-rod S, hanger T, yoke U V, wheel W, and arms X, all made substantially as and for the purpose set forth.

CONRAD DE STAEBLER.
